UNITED STATES PATENT OFFICE

GLENN W. CARPENTER, OF SCHENECTADY, NEW YORK, ASSIGNOR TO GENERAL ELECTRIC COMPANY, A CORPORATION OF NEW YORK

RECEIVING APPARATUS

Application filed April 25, 1924. Serial No. 709,066.

My present invention relates to receiving apparatus for high frequency signals, and more particularly to vacuum tube receiving equipment.

One of the objects of my invention is to provide a receiving apparatus which will be compact and one in which the length of the leads which connect the vacuum tubes to other apparatus will be reduced to a minimum. A further object of my invention is to provide an apparatus in which the electrical connections may be readily made and in which a portion at least of the auxiliary apparatus used in connection with the vacuum tubes and the connections to that apparatus will be securely protected from mechanical injury and from corrosion or oxidation.

The novel features which I believe to be characteristic of my invention are set forth with particularity in the appended claims. My invention itself however will best be understood by reference to the following description taken in connection with the accompanying drawing in which Fig. 1 is a longitudinal vertical cross section of an apparatus embodying my invention; Fig. 2 is a plan view of the same with a portion of the cover broken away; and Fig. 3 is a transverse cross-section along the line 3—3 of Fig. 1.

I have shown in the drawing a receiving apparatus employing six vacuum tubes of the three-electrode type. The sockets for the vacuum tubes and a plurality of electrical devices employed in the circuit connections for the tubes are enclosed in a receptacle 4, which is preferably of conducting material but which may be made of insulating material if desired. A block of slab 5 of insulating material fits into the top of the receptacle 4, this block 5 being secured by means of screws 6 to a cover 7, which entirely closes the top of the receptacle and is secured thereto by screws 8.

The block 5 of insulating material is provided with openings 9 for receiving the bases of vacuum tubes and the cover 7 is provided with openings 10, which register with the openings 9 in the block 5. Grooves 11 are provided in the block 5 on one side of each of the openings 9 and the cover 7 is provided on

one side of each opening 10 with a notch 12, which registers with a corresponding groove 11. The necessary contact springs 13 for making contact with the terminals of the vacuum tube base are secured to the under side of the block 5 by means of rivets 14. When the vacuum tube base is inserted in one of the openings in the cover and block 5 the usual pin on the side of the base is inserted through the notch 12. The tube may then be rotated and the pin will engage the under side of the cover 7 and hold the terminals on the tube base in good contact with the springs 13. To prevent any accidental release of the tube from good contact the metal of the cover adjacent the notches 12 is pressed downwardly, as indicated at 15, so that a tube cannot readily be rotated and removed without first exerting a downward pressure on the tube to permit the pin to move past the downwardly projecting portion 15 of the cover.

Suspended from the block 5 are a plurality of electrical devices which may be connected in the circuits of the vacuum tubes. The particular circuit connections employed in the apparatus illustrated form no part of my present invention and therefore the specific circuit connections are not illustrated or described. My invention is obviously applicable to any circuit connection desired. Among the different pieces of apparatus indicated in the drawing are four transformers 16, 17, 18 and 19, adapted for use in transforming high frequency currents. A single set of punchings held together by rivets 20 is employed for completing the magnetic circuits of all of these transformers. Two other transformers 21 and 22 adapted for audio frequency transformation are also shown. The transformers are all suspended from the block 5 by means of screws 23 extending through the block 5 and into the upper edges of the transformer cores. These screws are surrounded by spacing tubes 24 for preserving a desired spacing between the transformers and the under side of block 5.

Two parallel strips 25 of insulating material are secured to the core of the high frequency transformers by means of rivets 26.

A plurality of notches are provided in these strips 25 for engaging and holding condensers 27, which are included in the vacuum tube circuit connections. Each of the contact springs 13 is provided with a suitable terminal for making desired soldered connections between the vacuum tubes and the apparatus within the receptacle as well as for making connections from the vacuum tubes and apparatus within the receptacle to the operating batteries and other portions of the receiving system which cannot conveniently be enclosed in the receptacle. Some of these terminals, as for example, the terminals marked 28, extend upwardly from the block 5. Other terminals marked 29 extend downwardly into the receptacle a considerable distance. The block 5 also carries some additional terminals 30, which extend downwardly into the receptacle. In addition to the apparatus already described I have indicated at 31 a grid leak which is connected to two of the downwardly extended terminals.

All of the connections between the vacuum tubes and the apparatus within the receptacle 4 and the other portions of the receiving system may be made by conductors 32. Some of these conductors are connected to terminals on top of the block 5 and others are connected to terminals on the under side of block 5 and extended to the top of the block through suitably located holes therein. All of the conductors 32 extend downwardly through an overhanging portion 33 of the block 5, this overhanging portion being covered by the cover 7 so that when the apparatus is assembled none of the wiring within the receptacle is exposed to mechanical injury or the collection of dust. Neither is there any danger of breaking any of the connections by pulling on the conductors 32. The arrangement of apparatus shown is also so compact that the length of leads required between the different devices is reduced to a minimum.

After all of the electrical connections for the apparatus to be enclosed in the receptacle 4 have been made and tested, the receptacle 4 is partly filled with a hot molten insulating material which becomes solid when cold, such for example, as rosin. The assembled unit is then inserted in the receptacle and the insulating material allowed to harden. In the apparatus illustrated this insulating material 34 fills all of the space within the receptacle to a level which is above the tops of the transformers. Under some circumstances the condensers 27 may also be surrounded by the solidified insulating material. All of the connections from the coils of the transformers are made to the downwardly extending terminals so that when the unit is completed all of these connections are surrounded by the solidified insulating material and thus completely protected from mechanical injury as

well as from exposure to the air and consequent oxidation or corrosion. The terminals of some of the condensers 27 also extend downwardly in order that the connections thereto may be similarly protected. As a result the only soldered connections which are exposed to the air are comparatively massive and rigid connections such as those which may be made between the conductors 32 and the terminals carried on the upper side of block 5.

While I have shown and described only one embodiment of my invention, it is apparent that many modifications may be made in the construction and arrangement of the apparatus without departing from the scope of my invention as set forth in the appended claims. It is also apparent that my invention is in no way dependent upon the use of any particular circuit connection but that it may be used with a great multiplicity of circuit connections.

What I claim as new and desire to secure by Letters Patent of the United States is:—

1. The combination in a high frequency signal receiving apparatus of a receptacle, a block of insulating material which fits into the top of said receptacle, said block being provided with a plurality of openings for receiving the bases of vacuum tubes, and a plurality of electrical devices suspended from the under side of said insulating block, the space within said receptacle surrounding said devices being filled with a solid insulating material.

2. The combination in a high frequency signal receiving apparatus of a receptacle, a block of insulating material which fits into the top of said receptacle, said block being provided with a plurality of openings for receiving the bases of vacuum tubes, contact springs secured to the under side of said block for making contact with vacuum tube terminals, and a plurality of electrical devices suspended from the under side of said insulating block, the space within said receptacle surrounding said devices being filled with a solid insulating material.

3. The combination in a high frequency signal receiving apparatus of a receptacle, a block of insulating material which fits into the top of said receptacle, said block being provided with a plurality of openings for receiving the bases of vacuum tubes, a plurality of electrical devices suspended from the under side of said insulating block, and a cover for said receptacle having openings therein which register with the openings in said block of insulating material.

4. The combination in a high frequency signal receiving apparatus of a receptacle, a block of insulating material which fits into the top of said receptacle, said block being provided with a plurality of openings for receiving the bases of vacuum tubes, contact

5 springs secured to the underside of said block for making contact with vacuum tube terminals, a plurality of electrical devices suspended from the under side of said insulating block, and a cover for said receptacle having openings therein which register with the openings in said block of insulating material.

10 5. The combination in a high frequency signal receiving apparatus of a receptacle, a block of insulating material which fits into the top of said receptacle, said block being provided with a plurality of openings for receiving the bases of vacuum tubes, contact springs secured to the under side of said block for making contact with vacuum tube terminals, a plurality of electrical devices suspended from the under side of said insulating block, a cover for said receptacle having openings therein which register with the openings in said block of insulating material, and a notch in said cover on one side of each of the openings therein for receiving a pin in the base of a vacuum tube which pin will engage with the under side of said cover when the tube is rotated and hold the terminals of the tube base in good contact with said contact springs.

15 6. The combination in a high frequency signal receiving apparatus of a receptacle, a block of insulating material which fits into the top of said receptacle, two parallel strips of insulating material suspended from the under side of said block and a plurality of electrical devices secured to said strips.

20 7. The combination in a high frequency signal receiving apparatus of a receptacle, a block of insulating material which fits into the top of said receptacle, two parallel strips of insulating material suspended from the under side of said block, and a plurality of electrical devices which are engaged in suitable notches cut in said strips.

25 8. The combination in a high frequency signal receiving apparatus of a receptacle, a block of insulating material which fits into the top of said receptacle, a pair of parallel strips of insulating material suspended from the under side of said block, and a plurality of condensers adapted for use in a high frequency signal receiving system and which are engaged in notches in said strips of insulating material.

30 9. The combination in a high frequency signal receiving apparatus of a receptacle, a cover for said receptacle, a block of insulating material which fits into the top of said receptacle and is secured to said cover, and a plurality of transformers adapted for use in a high frequency signal receiving system suspended from the under side of said insulating block, the space within said receptacle surrounding said devices being filled with a solid insulating material.

35 10. The combination in a high frequency

signal receiving apparatus of a receptacle, a block of insulating material which fits into the top of said receptacle, a pair of strips of insulating material suspended from the under side of said insulating block, said block being provided with a plurality of openings for receiving the bases of vacuum tubes, contact springs secured to the under side of said block for making contact with vacuum tube terminals, a plurality of electrical devices secured to said strips of insulating material, and a plurality of terminals carried by said block whereby electrical circuit connections may readily be made between the vacuum tube contact springs, the devices within the receptacle and other devices outside of the receptacle.

40 11. The combination in a high frequency signal receiving apparatus of a receptacle, a block of insulating material which fits into the top of said receptacle, a pair of strips of insulating material suspended from the under side of said insulating block, a plurality of electrical devices which are engaged in suitable notches cut in said strips, said block being provided with a plurality of openings for receiving the bases of vacuum tubes, contact springs secured to the under side of said block for making contact with vacuum tube terminals, a plurality of transformers adapted for use in a high frequency signal receiving system suspended from the under side of said block, and a plurality of terminals carried by said block whereby electrical circuit connections may readily be made between the vacuum tube contact springs, the devices within the receptacle and other devices outside of the receptacle.

45 12. The combination in a high frequency signal receiving apparatus of a receptacle, a block of insulating material which fits into the top of said receptacle, a pair of strips of insulating material suspended from the under side of said insulating block, a plurality of electrical devices which are engaged in suitable notches cut in said strips, said block being provided with a plurality of openings for receiving the bases of vacuum tubes, contact springs secured to the under side of said block for making contact with vacuum tube terminals, a plurality of transformers adapted for use in a high frequency signal receiving system suspended from the under side of said block of insulating material, and a plurality of terminals carried by said block whereby electrical circuit connections may readily be made between the vacuum tube contact springs, the devices within the receptacle and other devices outside of the receptacle, the space within said receptacle surrounding said transformers being filled with a solid insulating material.

50 13. The combination in a high frequency signal receiving apparatus of a receptacle, a cover for said receptacle, a plurality of radio

transformers suspended from said cover, the space within said receptacle surrounding said devices being filled with a solid insulating material and a plurality of sockets for vacuum tubes carried by said cover.

14. The combination in a high frequency signal receiving apparatus of a receptacle, a block of insulating material which fits into the top of said receptacle, contact springs secured to the under side of said block and adapted to make contact with vacuum tube terminals, and a plurality of radio transformers supported from the under side of said block, the space within said receptacle surrounding said transformers being filled with a solid insulating material.

15. The combination in a high frequency signal receiving apparatus of a receptacle, a block of insulating material which fits into the top of said receptacle, contact springs secured to the under side of said block and adapted to make contact with vacuum tube terminals, a plurality of radio transformers supported from the under side of said block, and terminals carried on the under side of said block to which the coils of said transformers are connected, said transformers and connections of the coils thereof to said terminals being surrounded by solid insulating material.

16. The combination in a high frequency signal receiving apparatus of a receptacle, a block of insulating material which fits into the top of said receptacle, and a plurality of transformers adapted for use in a high frequency signal receiving system secured to and suspended from the under side of said block of insulating material, terminals carried by said block to which the coils of said transformers are connected, said transformers and the connections of the coils thereof to said terminals being surrounded by a solid insulating material.

17. The combination in a high frequency signal receiving apparatus of a receptacle, a cover for said receptacle, a plurality of transformers adapted for use in a high frequency signal receiving system located within said receptacle, terminals carried by said cover to which the coils of said transformers are connected, said transformers and the point of connection of the coils thereof to said terminals being surrounded by a solid insulating material.

18. The combination in a high frequency signal receiving apparatus of a receptacle, a block of insulating material which fits into the top of said receptacle, a plurality of electrical devices suspended from the under side of said insulating block, said block being provided with a plurality of openings for receiving the bases of vacuum tubes, contact springs secured to the under side of said block for making contact with vacuum tube terminals, and a plurality of terminals car-

ried by said block whereby electrical circuit connections may readily be made between the vacuum tube contact springs, the devices within the receptacle and other devices outside of the receptacle, a portion at least of said devices and the connections thereof to said terminals being surrounded by a solid insulating material.

In witness whereof, I have hereunto set my hand this 23rd day of April, 1924.

GLENN W. CARPENTER.
